UNITED STATES PATENT OFFICE.

EMERY LESLIE LAWLOR, OF YOUNGSTOWN, OHIO.

DESIGN FOR A TIRE.

58,494.

Specification for Design.

Patented July 26, 1921.

Application filed December 9, 1920. Serial No. 429,591. Term of patent 7 years.

To all whom it may concern:

Be it known that I, EMERY LESLIE LAWLOR, a citizen of the United States, residing at Youngstown, in the county of Mahoning and State of Ohio, have invented a new, original, and ornamental Design for a Tire, of which the following is a specification, reference being had to the accompanying drawing, forming a part thereof.

Figure 1 is a fragmentary elevation looking toward the tread portion of the tire.

Fig. 2 is a sectional view on the line 2—2 of Fig. 1.

I claim:

The ornamental design for a tire, as shown.

EMERY LESLIE LAWLOR.
